United States Patent Office

Des. 227,828
Patented July 24, 1973

227,828

CHILD'S CAR SEAT

Donald C. Heyl, 11 Via Seville, Rolling Hills Estates,
Calif. 90274, and Harry R. Gillespie, 1200 S. Orange
Grove, Apt. 16, Pasadena, Calif. 91105

Filed Oct. 18, 1971, Ser. No. 190,429

Term of patent 14 years

Int. Cl. D6—01

U.S. Cl. D6—9

FIG. 1.

FIG. 2.

FIG. 3.

FIG. 4.

FIG. 5.

FIG. 1 is a perspective view of a child's car seat showing our new design;

FIG. 2 is a right side elevational view thereof;

FIG. 3 is a front elevational view thereof;

FIG. 4 is a rear elevational view thereof; and

FIG. 5 is a top plan view thereof.

We claim:

The ornamental design for child's car seat, as shown.
